UNITED STATES PATENT OFFICE.

ALBERT NELSON, OF NEW YORK, N. Y.

DEVICE FOR SUSPENDING MILK-BOTTLES.

1,205,655.

Specification of Letters Patent. Patented Nov. 21, 1916.

Application filed March 22, 1916. Serial No. 85,985.

To all whom it may concern:

Be it known that I, ALBERT NELSON, a citizen of the United States, residing at New York city, in the county of New York, State 5 of New York, have invented certain new and useful Improvements in Devices for Suspending Milk-Bottles; and I do hereby declare the following to be a full, clear, and exact description of the invention, such as 10 will enable others skilled in the art to which it appertains to make and use the same.

This invention relates to improvements in bottle holders, and particularly to devices for suspending milk bottles.

15 One object of the invention is to provide a device of this character which will effectively support a milk bottle and at the same time prevent the theft of the same.

Another object is to provide a device of 20 this character which can be quickly and easily opened to remove the bottle by the occupant of the house, or other authorized person.

Other objects and advantages will be apparent from the following description when taken in connection with the accompanying drawing.

In the drawing: Figure 1 is a side elevation of my improved bottle suspending device and lock; Fig. 2 is a top plan view of the same; Fig. 3 is a top plan view showing the device in open position; Fig. 4 is a horizontal section on the line 4—4 of Fig. 1.

Referring particularly to the accompanying drawing, 10 represents a ring at one side of which there are formed a pair of attaching ears 11 for the reception of suitable fastening devices whereby the device can be secured to the outer face of a door. This 35 ring has a movable section 12, hinged as at 13 and provided on its other end with a projecting lug 14, having a shoulder 15 formed on its outer end. In the other abutting end of the ring there is formed a channel 16 40 which extends around the inner portion of the ring and through an opening 17 between the attaching ears. In the door, and registering with this opening is an opening 18. Mounted in the inner portion of the ring, 45 and in the outer end of the channel, is a resilient hook latch 19 which is adapted to engage with the shoulder of the lug 14 when

said lug enters the outer end of the channel. Attached to this latch and extending along the channel and through the said openings to 55 a point inwardly of the door is a cord 20, by means of which the latch may be moved out of engagement with the shoulder to permit the movable section of the ring to be swung to one side, for the introduction or 60 removal of the neck of a milk bottle. Normally, the movable section is held in open position by a coil spring 21 located in the hinge 13 so that the milkman can readily insert the neck of a milk bottle within the 65 ring, and then swing the movable section into locked position. The bottle will then be suspended by a flange, and cannot be removed by an unauthorized person. To remove the bottle, the occupant opens the door, 70 grasps the bottle with one hand, and then reaches around the door within the house and pulls the cord. This moves the latch out of operative position, and permits the movable section to be swung into open position by an outward pressure thereagainst 75 with the neck of the bottle.

What is claimed is:

1. A bottle holder comprising a ring having a hinged section, means for securing the 80 ring to a support, latching means between the separable ends of the sections of the ring and a releasing element connected to the latching means and extending through the ring and the support. 85

2. A bottle supporting device comprising a ring including hingedly connected sections, one of the sections being arranged to be secured to a support and having a channel extending part way therethrough and 90 through the support, a resilient latch member in the outer end of the channel, a hook lug on the abutting end of the other section for entrance into the channel and for engagement with the latch, and a flexible element connected to the latch and extending through the channel and support. 95

In testimony whereof, I affix my signature, in the presence of two witnesses.

ALBERT NELSON.
